UNITED STATES PATENT OFFICE.

EDWARD SAMUEL AND VICTOR ANGERER, OF PHILADELPHIA, PENNSYLVANIA, ASSIGNORS TO WILLIAM WHARTON, JR., & COMPANY, OF SAME PLACE.

OVERHEAD-RAILWAY SWITCH.

SPECIFICATION forming part of Letters Patent No. 364,548, dated June 7, 1887.

Application filed March 16, 1887. Serial No. 231,104. (No model.)

To all whom it may concern:

Be it known that we, EDWARD SAMUEL, a citizen of the United States, and VICTOR ANGERER, a subject of the Emperor of Austria, 5 and both residing in Philadelphia, Pennsylvania, have invented certain Improvements in Overhead-Railroad Switches, of which the following is a specification.

The object of our invention is to so construct 10 an overhead-railroad switch as to avoid sharp curves or angles, to provide for the automatic operation of the switch-rail when the truck is approaching the open switch on either the main rail or siding rail, and to permit the ready operation of the switch-rail by hand when the truck is traveling in the opposite direction. This object we attain in the manner hereinafter set forth, reference being had to the accompanying drawings, in which—

o Figure 1 is a sectional plan view of our improved overhead-railroad switch. Fig. 2 is a side view of the same, and Fig. 3 is a perspective view of the automatic shifting device.

A is the switch-rail; B B', the main rail, having 25 its continuity interrupted, as shown in Fig. 1, for the reception of the switch-rail; and D is the siding-rail.

The switch-rail A is pivoted at *a* to a bracket, C, which also serves to support the end of the rail 30 B, and projecting segmental arms *b* *b'* are secured to the switch-rail A and pass through guide-openings in brackets C' C'', the bracket C' also supporting the end of the siding-rail D. A bracket, C'', supports the end of the main rail B', 35 and has a lug, *c*, which projects beneath the arm *b* of the switch-rail and aids in supporting the movable end of the said rail when the latter is in the position shown by full lines in Fig. 1.

It will be noted on referring to Fig. 1 that the 40 rail B is in a line, *x*, about midway between the rails B' and D, thus avoiding the sharp corner that would be formed at *m* if the rails B B' were on a straight line and the switch-rail was moved to coincide with the siding-rail D. By this 45 means we avoid the jarring of the carrying-truck when the latter passes from the main rail to the switch-rail, or vice versa.

Another feature of our invention is the device 50 for automatically setting the switch when the carrying-truck is approaching the switch and

the latter is open—that is to say, when the switch-rail is not set to coincide with the rail which is being traversed by the truck.

A shaft, E, having its bearings in brackets C', has at its upper end a chain-wheel, *e*, and at its 55 lower end a crank-arm, *e'*, which is connected to a lug, *a'*, on the switch-rail A by a link, *e*'. Passing around the chain-wheel *e* and over guide-pulleys *f* on the brackets C' C'' is a chain, *g*, one end of which is secured to an arm, *h*, of a 60 rock-shaft, H, having its bearings in a bracket on the rail B', the other end of the chain being secured to an arm, *i*, of a rock-shaft, I, adapted to turn in a bracket on the rail D, a continuation, *g'*, of the chain depending from each of the 65 arms and being provided with a counterbalance-weight, *g''*, to take up the slack in the chain.

The rock-shaft H is provided with an arm, *h'*, which, when raised, is in the path of the truck M when the latter is traversing the rail B', and 70 the rock-shaft I is also provided with an arm, *i'*, which, when raised, is in the path of the truck M when traversing the rail D.

The extensions *g'* of the chain *g* are within 75 easy reach of an attendant, so that he can, by pulling one or other of the chains *g'*, throw the switch-rail A into line with either the rail B' or the rail D, as may be required; but if the switch-rail is in the position shown by full lines in Fig. 1—that is to say, in line with the rail B'—the 80 arm *i'* of the rock-shaft I will be raised, as shown in Fig. 2, and the arm *h'* of the rock-shaft H will be depressed.

If a truck M of the ordinary construction 85 is traveling on the rail D in the direction of the arrow, Fig. 2, its front wheel will come in contact with the projecting arm *i'*, depressing it, and at the same time moving the chain *g* and consequently the chain-drum and its shaft, so as to throw the switch-rail from the position 90 shown by full lines in Fig. 1 to that shown by dotted lines, or into line with the rail D, the same movement throwing up the arm *h'* of the rock-shaft H into position to be operated by a truck traversing the rail B'.

If the switch-rail is set in line with the rail D and a truck is approaching the switch on the rail B', the switch will be automatically set in the same manner, so that it will be impossible for the truck to run off either track. If the 95 truck

truck is traversing the switch-rail A in the direction of the arrow shown in Fig. 1, the switch-rail is set by the attendant so as to direct the truck to either of the rails B' or D.

- 5 The crank-arm e' is provided with two stop-lugs, n n', which come in contact with a pin, p, on the bracket C', and limit the movement of said arm in either direction, the lugs being such that the arm, when stopped at either limit of 10 its movement, is in such position as to prevent any accidental movement of the switch-rail by lateral pressure exerted thereupon.

We claim as our invention--

1. The combination of the main rails, the 15 siding-rail, and the switch-rail of an overhead-railway track, with a shaft connected to the switch-rail and having a chain-drum, trips adjacent to the main and siding rail, and a chain adapted to the drum and connected to 20 said trips, all substantially as specified.

2. The combination of the main rails, the siding-rail, and the switch-rail of an overhead-railway track, trips adjacent to the main rail and siding-rail, means whereby the movement 25 of either of said trips is transmitted to the switch-rail, and chains depending from each trip and serving as a means of operating the switch-rail by hand, all substantially as specified.

3. The combination of the main rails, the 30 siding-rail, and the switch-rail of an overhead-railway track, trips adjacent to the main rail and siding-rail, means whereby the movement of either of said trips is transmitted to the switch-rail, and chains depending from the 35 trips and provided with weights, all substantially as specified.

4. The combination of the fixed main rails and siding-rail and their supporting-brackets, with the pivoted switch-rail having projecting 40 segmental bars, and brackets having openings for the reception and guidance of said bars, all substantially as specified.

5. The combination of the main" rails, the siding-rail, and the switch-rail of an overhead- 45 railway track, with a shaft having a crank-arm connected to the switch-rail and provided with stop-lugs, all subsfiantially as specified.

In testimony whereof we have signed our names to this specification in the presence of 50 two subscribing witnesses.

EDWD. SAMUEL.
VICTOR ANGERER.

HARRY SMITH.

Correction in Letters Patent No. 364,548.

It is hereby certified that the name of the assignee in Letters Patent No. 364,548 granted June 7, 1887, upon the application of Edward Samuel and Victor Angerer, of Philadelphia, Pennsylvania, for an improvement in "Overhead Railway Switches," was erroneously written and printed "William Wharton, Jr., & Company;" that said name should have been written and printed *William Wharton, Jr., and Company, Incorporated;* and that the said Letters Patent should be read with this correction therein that the same may conform to the record of the case in the Patent Office.

Signed, countersigned, and sealed this 28th day of June, A. D. 1887.

[SEAL.]

D. L. HAWKINS,

Acting Secretary of the Interior.
